CLAIM

The ornamental design for a juicer filter, as shown and as described.

DESCRIPTION

FIG. 1 is a perspective view of a juicer filter showing my new design;

FIG. 2 is a front view thereof;

FIG. 3 is a rear view thereof;

FIG. 4 is a left end view thereof;

FIG. 5 is a right end view thereof;

FIG. 6 is a top view of thereof;

FIG. 7 is a bottom view thereof; and,

FIG. 8 is another perspective view thereof.
